UNITED STATES PATENT OFFICE.

BARTON B. WARD, OF NEW YORK, N. Y., ASSIGNOR TO THE ELECTRIC CONSTRUCTION AND SUPPLY COMPANY, OF SAME PLACE.

ELECTRIC-LIGHTING SYSTEM.

SPECIFICATION forming part of Letters Patent No. 447,482, dated March 3, 1891.

Application filed May 5, 1890. Serial No. 350,599. (No model.)

To all whom it may concern:

Be it known that I, BARTON B. WARD, a citizen of the Dominion of Canada, residing at New York city, in the county and State of New York, have invented a new and useful Improvement in Regulators for Electric-Light Systems, of which the following is a specification.

The invention relates to means for maintaining the resistance practically equal and constant in several multiple-arc branches, including translating devices—for example, arc or incandescent lights.

My invention consists in the arrangement of circuits and in the apparatus hereinafter described and claimed.

In the accompanying drawings, Figures 1, 2, and 3 are diagrams of several systems embodying my invention.

In order that the current in the several multiple-arc branches shall be constant, it is essential that their resistances shall remain constant. To this end when a lamp is thrown out of use an equivalent resistance may be substituted. This has sometimes been done at each lamp by means of a number of resistance devices—that is, one for each lamp in the system—and these resistances have been made as nearly equal to the normal lamp resistance as could be readily done. With this arrangement the difficulty and expense of preserving an exact balance in the several branches have been considerable, and by my invention the difficulty and expense are largely reduced. I may use the individual resistances above referred to at each lamp; but in that case it is unnecessary to carefully gage each resistance to equal that of its lamp. It is only necessary to make them approximately of the proper resistance and the system will be automatically balanced at a point external to the lamps and at one point for all the lamps in the two branches.

Referring especially to Fig. 1, G is a generator, and 1 2 the main circuit wires or leads. At some convenient point in the system where multiple-arc branches are led to translating devices is placed a regulator 3, which consists, essentially, of an artificial resistance and means for transferring resistance from one branch to another as the necessity arises. $R h$ is such resistance, shown in this instance

as a strip or rod of high-resistance material. Different forms of resistance are shown in Fig. 3. When the resistances of branches 4 and 5 are equal, the contact 6 of the circuit-controller to which line 1 is connected by a flexible or movable connection will be held at the center of $R h$. When, however, the resistance increases in either line, the coil 7 or 8, as the case may be, in the other line will be more strongly energized and will move the core to cut out resistance from said first line into the other line, thus at once equalizing resistance in the two lines or branches and maintaining the remaining lights at their normal intensity. The coils are preferably wound on insulating-spools, so that there may be no danger of cross-connection between the core and the branches 4 5. In branch 4 are shown several arc lamps 9 and in branch 5 several incandescent lamps 10. The lamps will preferably, though not necessarily, be provided with a resistance $R h^2$ in a cut-out branch, which should be approximately equal to the resistance of a normal arc. The circuits of the first lamp are diagrammatically indicated. 11 is the main magnet. 12 is a magnet with a small number of turns also in the main line and serving during the normal operation of the lamp to hold its armature away from the contact 14. 15 is the shunt-magnet of the lamp, and the circuit therefrom passes to a coil on magnet 12, so wound as to have an opposite magnetic effect from the main-line coil. When, therefore, the current in the shunt becomes strong enough to neutralize the attractive force of magnet 12, as would be the case, for example, if one carbon should be broken, so as to open the circuit between the two carbons, the armature will move to its back-stop and close the circuit through $R h^2$; but it will be understood that this action does not occur during the ordinary operation of the carbon-feeding apparatus of the lamp. If resistance $R h^2$ is just equal to the resistance of a normal arc, the contact 6 of regulator 3 will remain at the center of its resistance. If, however, as is generally the case, there is a difference, the contact 6 will be moved up or down and at once adjust the resistance, as before described. $R h^2$ could be omitted, especially in a system in which a small num-

ber of lamps—say three or four—are placed in each multiple-arc branch. The resistance R_h and the range of movement of contact 6 would then have to be greater, and the regulation would not be so quickly and perfectly attained.

Fig. 2 shows a modification of the regulator. Each coil 7 8 has a separate contact 6', co-operating with a separate resistance. 10 There is a flexible connection 16 between the line and the sliding contacts, and as said contacts of the circuit-controller move more or less of the resistance is shunted, as will be apparent from the drawings. It will be understood that the lamps in this arrangement are preferably provided with resistances corresponding to R_h^2 of Fig. 1. When one or 15 more of the lights in branch 4 are thrown out of use, if it increases the resistance, more current is thrown to coil 8, which will move 6' upward, throwing resistance into its branch. At the same time the weakening of coil 7 will permit contact 6 to move downward, cutting out resistance from its branch, and thus the 20 balance is immediately re-established in the system.

Fig. 3 shows another application and a further development of the invention. The regulator 3 controls the resistance of branches 4 5, 30 which may include lamps, as above described. The branch 4 is subdivided into two branches 4' 5', the former including arc and the latter incandescent lamps, (or both including lamps of the same character, or other translating devices, if desired.) At the point of division is placed a regulator, similar to regulator 3, for controlling the resistance of sub-branches 4' 5'. Branch 5 is also subdivided into two branches 4" 5" in the same manner and is 40 provided with a resistance regulator at the point of division. The operation of these systems will be apparent without further description.

The invention is especially valuable in circuits having arc lamps in one branch and incandescent lamps in the other, as indicated in Fig. 3.

Having thus described my invention, what I claim is—

50 1. In an electric-lighting system, the combination of the main wires orleads, multiple-arc branches containing translating devices, a resistance-regulator for each pair of branches

between one of the leads and the translating devices, said regulator comprising a coil in 55 each branch, a resistance, part of which is in one branch and part of which is in a second branch, and a contact connected with one of the line-wires bearing on said resistance and moved by the coils to throw resistance from 60 one branch to the other, substantially as described.

2. In an electric-lighting system, the combination of a main circuit, one or more pairs of multiple-arc branches, said branches, or 65 either of them, containing translating devices provided with cut-out resistances approximately equal to the normal resistance of said translating devices, and an automatic resistance-regulator between one main wire and 70 said translating devices, consisting of a resistance divided between the branches, and coils in said branches controlling a contact-bearing on the resistance between the points where the branches are connected, whereby 75 movement of said contact throws resistance out of one branch and into the other, substantially as described.

3. A resistance-regulator consisting of a resistance the two terminals of which are connected through coils to two lines, in combination with a contact connected to the source of current bearing on the resistance between the two terminals and controlled by the armature of the coils, whereby resistance is thrown from 80 one line to the other as required, substantially as described.

4. In an electrical lighting system, the combination of the main wires, multiple-arc branches containing translating devices, a resistance-regulator for each pair, consisting of a coil in each of said branches, a resistance in 90 each branch, said resistances being substantially equal when the working-resistances of the branches are equal, and circuit-controlling 95 devices moved by the coils for simultaneously cutting resistance out of one branch and cutting resistance into the other branch, substantially as described.

This specification signed and witnessed this 100
7th day of March, 1890.
